UNITED STATES PATENT OFFICE.

JOHN H. BECK, OF SALT LAKE CITY, UTAH.

SHOE-POLISHING MACHINE.

1,254,965.

Specification of Letters Patent. Patented Jan. 29, 1918.

Application filed April 24, 1917. Serial No. 164,236.

To all whom it may concern:

Be it known that I, JOHN H. BECK, a citizen of the United States, residing at Salt Lake City, in the county of Salt Lake and

5 State of Utah, have invented new and useful Improvements in Shoe-Polishing Machines, of which the following is a specification.

This invention relates to shoe polishing machines, and has for its primary object to 10 provide a machine which operates automatically after once being started.

Another object is to provide a shoe polishing machine of a durable and compact construction which first cleans the shoes and 15 then polishes the same.

With these and other objects in view which will be hereinafter fully described and particularly pointed out in the claims, the invention consists in the mechanism 20 illustrated in the accompanying drawings forming a part of this specification, in which:

Figure 1 is a vertical longitudinal section of the same,

25 Fig. 2 is a partial horizontal sectional view of the same on the line *b*—*b* of Fig. 1, having parts of the structure thereof broken away,

30 Fig. 3 is a horizontal sectional view of the device on the line *c*—*c* of Fig. 1, showing diagrammatically the wiring plan of the device,

35 Fig. 4 is a vertical section in front elevation on the line *d*—*d* of Fig. 1,

Fig. 5 is a vertical sectional elevation of the controlling means on the line 6—6 of Fig. 3,

40 Fig. 6 is a vertical section in rear elevation of the means for actuating the tilting frame, as hereinafter described,

Fig. 7 is an enlarged partial top plan view of one of the reciprocating brush elements of the device,

45 Fig. 8 is a sectional side elevation of the extensible coupling of the drive shaft of the supplemental polishing element of the device,

Fig. 9 is a side elevation in partial section of the reversible driving means of the supplemental polishing element of the device,

50 Fig. 10 is a side elevation of one of the shoe supports of the device,

Fig. 11 is a sectional rear elevation of the cams for actuating the bellows of the polish 55 applying means,

Fig. 12 is an enlarged rear elevation of

one of the polish reservoirs part of the same being broken away to show one of the spraying nozzles thereof,

Fig. 13 is an enlarged longitudinal sectional view of one of the winding spools of the supplemental polishing mechanism and its correlated parts.

Like characters of reference indicate like parts in the various views.

In the drawings 1 designates a body in which the mechanism is housed. A platform 2 is provided at the front end of the body, and a seat 3 is built upon the body facing the platform 2. An aperture 4 is formed in the platform 2 in a convenient position relative to the seat 3. A pair of shoe supports 5 are located in the body directly underneath the aperture 4 and are adapted to conveniently support the shoes of a person sitting on the seat 3. The shoe supports 5 are stationary and are secured to a bottom 6 of the body 1. Said shoe supports 5 are formed to engage the underside of shoes 7 resting thereon, and have projections 8 formed thereon adapted to engage the front end of the heel of the shoes to properly position the shoes upon said shoe supports.

It will be noted, by reference to Figs. 2 and 3 of the drawings, that the inclosure of the body 1 is divided into a number of compartments by partitions and to protect the various mechanisms located therein and to afford means for conveniently securing said mechanism in the body. A transverse vertical partition 9 is disposed within the body adjacent the rear edge of the aperture 4. A horizontal transverse portion 10 is disposed within the body some distance below the top of the shoe supports 5, and a second horizontal transverse partition 11 is formed in said body in the plane of the platform 2. These partitions are cut away at various points, as will be hereinafter described to allow the various parts of the mechanism to operate therethrough.

A shaft 13 is disposed transversely of the body and is mounted upon bearings 14 secured to the upper surface of the partition 10. Disks 15 are mounted upon opposite ends of the shaft 13 and constitute fly-wheels, for the mechanism. A pair of guides 16 are mounted upon the partition 10 and extend longitudinally of the body in front of the disks 15. A block 17 is mounted in each guide and is adapted to move thereon. A pitman rod 18 is provided for each block

and has its front end pivotally mounted upon said block and its rear end pivotally mounted upon a stud 19 secured upon the respective disk 15. Rods 20 have their rear 5 ends secured to their respective block 17 and extend forward thereof through an aperture 21 of the guide structure. The front ends of the rods 20 are bifurcated, as designated at 23, and lie in a horizontal plane. A brush member 24 is pivotally mounted for horizontal 10 swinging movement on each arm of said bifurcated ends 23. The bristles 25 of each brush member 24 are disposed upon the side thereof facing the brush mounted upon the 15 opposite arm of the bifurcated end. Flat spring members 26 are mounted upon the outer side of each arm of the bifurcated end, and extend forward therefrom to engage the brush members 24 and to retain each pair 20 thereof in close relation with each other. A coil spring 27 is also provided to retain each pair in close relation with each other, and has its ends secured to the opposite brush members 24. Stops 27' are formed on each 25 arm of said bifurcated ends 23 to limit the movement of the brush members 24. When the shaft 13 is rotated the brushes 24 are reciprocated, and are so disposed that they will engage the sides of a pair of shoes resting upon the shoe supports 5 with their bristles 25. The bristles 25 are formed so that they will engage all of the lower surfaces of the shoes. It will be noted in this regard that the front and rear portions of the bristles 25 are relatively longer, as designated at 28, so that in the reciprocations of the brushes 24 these longer bristles will engage the rear and front surfaces of the shoes and will thereby engage the entire lower 30 surfaces of the shoes. By reason of the fact that the brushes 24 have a hinged relation with their mates, the brushes will accommodate themselves to various sizes of shoes. An aperture is formed in the partition 9 to 35 allow the brushes 24 to reciprocate as herein described.

A motor 12 is mounted upon the upper surface of the partition 11 and has a sprocket 29 mounted upon its rotating shaft 30. A 50 sprocket 29' is mounted upon the shaft 13 adjacent disk 15 in alinement with said sprocket 29, and a chain 31 is trained over said sprockets to form a driving connection therebetween. Mounted upon the shaft 13 is 55 a spur gear 32. A shaft 33 is mounted in bearings 34 which are formed in respective extensions of the structure of the bearings 14. A spur gear 35 is journaled upon said shaft 33 and meshes with the gear 32, said 60 gears 32 and 35 being equal in size. Mounted upon the shaft 33 is a miter gear 36. A vertical shaft 37 is journaled in one of the extensions of the structure of bearings 14, and a miter gear 38 is mounted upon the 65 upper end of said shaft and meshes with

the miter gear 36. A shaft 39 is disposed longitudinally of the mechanism below the partition 10. A bearing 40 secured to the partition 10 supports the rear end of said shaft, and a bearing 41 mounted upon the bottom 6 supports the front end thereof. A miter gear 42 is mounted upon the lower end of the shaft 37 and meshes with a miter gear 43 mounted upon the rear end of the shaft 39. 75

The front end of the shaft 39 has a gear 44 mounted thereon. A shaft 45 has its rear end journaled in the structure of the bearing 41, and has a gear 46 meshing with the gear 44. The gear 46 is considerably larger than 80 the gear 44 for purposes hereinafter described. A double faced cam 47 is mounted upon the shaft 45 some distance in front of the gear 46. A cam groove 48 is formed upon the rear surface of the cam 47, and a cam groove 49 is formed upon the front surface of the cam 47. A cam lever 50 is provided, having a slot 51 formed therein engaging the shaft 45 between the gear 46 and said cam 47 and having a roller 52 rotatably mounted thereon and engaging the cam groove 48. The cam lever 50 is supported for horizontal sliding movement by the shaft 45 and a slide 53 formed upon the structure of bearing 41, and has a link 54 pivoted for 95 horizontal swinging movement at its outer end. A bellows 55 of usual construction is mounted upon the adjacent side of the body and is operated through the link 54. A cam lever 56 is disposed in front of the cam 47. 100 and has a slot 57 engaging said shaft 45. A roller 58 is rotatably mounted on said cam lever and engages the cam groove 49. Said cam lever 56 is supported by said shaft 45 and a slide 59 formed upon the structure of the bearing 60 in which the front end of the shaft 45 is journaled. The cam lever 50 is confined laterally between the rear surface of the cam 47 and the front surface of the gear 46. A gear 61, identical with the gear 46, 110 is mounted upon the shaft 45 just in the rear of bearing 60 for purposes hereinafter described, and the cam lever 56 is confined between the rear surface of said gear 61 and the front surface of the cam 47. The cam 115 lever 56 extends toward the other side of the body and has a link 62 mounted on its outer end for horizontal swinging movement. A bellows 63 of usual construction is mounted upon the adjacent side of the body, and is in operable connection with said link. The bellows 55 and 63 comprise stationary bottom members 64, movable top members 65 having one end hinged to said bottom members, flexible folding side elements 66 forming an inclosure with said top and bottom members, intakes 67 provided with check valves, and outlet pipes 68 provided with check valves. The bellows 55 and 63 are actuated by the cam 47 through the medium of 120 125 130

the cam levers 50 and 56 and the links 54 and 62, and, by reason of the contour of the cam grooves 48 and 49, are adapted to be actuated at different times for purposes hereinafter described.

A movable frame 69 is mounted upon the bottom 6 of the body for longitudinal sliding movement. This movable frame comprises a horizontal portion 70 and uprights 71 extending upwardly therefrom on either side of the horizontal portion. A transverse shaft 72 is journaled upon the uprights 71. A vertical shaft 73 is journaled on a bracket 74 of the frame 69 and has a bevel gear 75 mounted upon its upper end and meshing with a bevel gear 76 mounted upon the transverse shaft 72. Another bevel gear 77 is mounted upon the lower end of the shaft 73. A bearing 78 is formed upon the horizontal portion 70 of the movable frame and supports the front end of a shaft 79 disposed in alinement with the path of the frame 69. A bevel gear 80 is mounted upon the front end of said shaft and meshes with the bevel gear 77. A thrust collar 81 is mounted upon the shaft 79 and engages the rear surface of the bearing 78, and the shaft 79 is secured against lateral movement by said collar and the bevel gear 80 which engages the front surface of said bearing. A bearing 81' is mounted upon the partition 9 in axial alinement with the shaft 79. A sleeve 82 is journaled therein and has thrust collars 83 mounted thereon on either side of said bearing to prevent lateral movement. The rear end of the shaft 79 engages the front end of the aperture in said sleeve and is adapted for sliding movement therein. A key 84 is secured to said shaft and engages a longitudinal slot in said sleeve to provide a rotarial driving relation between said sleeve and said shaft. A shaft 85 engages the rear end of the aperture in the sleeve 82 and is adapted for longitudinal sliding movement therein. A key 86 is secured to said shaft 85 and engages a slot in said sleeve whereby a rotarial driving relation between said sleeve and said shaft is obtained. The rear end of said shaft 85 is secured within the hole of a sleeve 87. A bracket 88 is secured to the rear wall of the body and has a long stud 89 formed thereon in axial alinement with the shaft 85. The hole in the sleeve 87 is journaled upon said stud, and the rear end of said shaft 85 and the sleeve 87 are supported thereby. It will be noted that the shaft 85 and the sleeve 87 are adapted for longitudinal movement for purposes now to be described. A groove 90 is formed upon the outer surface of the sleeve 87. This groove forms a complete circuit comprising two parallel portions 91 formed spirally respecting the axis of said sleeve and semi-circular portions 92 connecting the respective ends of said parallel portions. A series

of spaced pins 93 are secured upon the surface of said sleeve between the parallel portions of said groove and are disposed in a line equidistant from the parallel portions of said groove, the end pins of said series being disposed coincident with the centers of said semi-circular portions of the groove. A vertical shaft 94 is journaled upon the structure of the adjacent bearing 14 and has a large bevel gear 95 mounted at its upper end and a relatively small bevel gear 96 is mounted upon the shaft 33 and meshes with said bevel gear 95. Mounted upon the lower end of the shaft 94 is a sprocket gear 97, the teeth of which are adapted to engage the successive pins in the series of pins 93. The lower end of the shaft 94 extends below the sprocket gear 97 and engages the groove 90 in the sleeve. When the shaft 94 is rotated the sprocket gear 97 engages successive pins 85 in the series of pins 93 and rotates the sleeve, and the sleeve, by reason of the inclination of the groove 90, is also moved longitudinally. When the sprocket gear 97 engages the end pins of the series and the shaft 94 enters the corresponding semi-circular portion of the groove. As the shaft passes through the semi-circular portion of the groove the engaged pin is swung around the sprocket gear and the shaft enters the other opposite parallel portion of the groove. The rotation of the shaft is reversed in this operation and the sleeve is rotated in the opposite direction until the other semi-circular portion of the groove is reached where the reversing operation is repeated. By the mechanism above described a means is provided for driving the shaft 85 alternately in opposite directions for purposes hereinafter set forth.

Pivottally mounted upon the transverse shaft 72 just inside the bearings of the uprights 71 are brackets 98. Said brackets 98 have bearings 99 formed therein disposed radially of the shaft 72. Shafts 100 are 110 journaled in said bearings 99 and have bevel gears 101 mounted upon the inner end thereof and engaging respective bevel gears 101' mounted upon the shaft 72. The brackets 98 extend along the shafts 100 and support the 115 outer ends thereof in bearings 102. A yoke 103 is pivotally mounted upon the shaft 72 at a point intermediate the ends thereof and has a rod 104 secured in a recess therein. The rod 104 has a bracket 105 secured thereon, a strut rod 106 secures the outer ends of each bracket 98 with said bracket 105. The rod 104 and the shafts 100 lie in the same plane. A shoulder 107 is formed upon the shafts 100 and engages the outer surface of 125 the bearings 102, and the shafts are secured against lateral movement between said shoulder 107 and the outer face of the gears 101. A spool 108 is rotatably mounted upon ball bearings 109 on the outer ends of the 130

shafts 100. A spiral spring 110 encircles each shaft 100 within the spools 108, and has its one end secured to its respective shaft and its other end secured to its respective 5 spool whereby a resilient driving connection is established between the shafts 100 and their respective spools. The spools 108 have deep flanges formed at their ends. A flexible belt polishing element 111 has one end 10 thereof secured to each respective spool and is of such length that a large portion may be wound upon either of the spools. The ends of this flexible belt polishing element are detachably secured to the spools by 15 means of a plate 112 and headed screws 113 which clamp the ends of the belt element between the plate and the body of the spool. In applying a polishing belt element upon the spools the springs 110 of the spools are 20 held sufficiently taut so that they tend to wind the belt element upon their respective spools. This winding tendency is transmitted to the portion of the belt polishing element which extends from one spool to the 25 other and it is stretched taut thereby. The rod 104 has an idle spool 114 journaled upon its end and lying in the plane of the spools 108. This spool contacts the belt polishing element at a point intermediate the 30 spools 108. Casings 115 partially inclose the spools 108 to prevent the belt polishing element from jumping over the flanges of the spools, and are secured upon the bearings 102.

35 It will be noted that a tilting frame is formed by the above described structure, comprising brackets 98, bracket 105, the yoke 103, the rod 104, and the strut rods 106, which is pivoted upon the shaft 72. The 40 position of this tilting frame is controlled in the following manner. On the under side of the bracket 105 a pivot bearing 116 is formed. A cam lever 117 has its upper end pivoted in said bearing 116 and extends 45 downwardly. A shaft 118 is journaled in a bearing 119 which is mounted on the horizontal portion 70 of the movable frame 69, said shaft being disposed parallel to the path of movement of said frame 69 and 50 lying in axial alignment with the shaft 39 hereinbefore described. The cam lever 117 has a slot formed in the lower end thereof which embraces the shaft 118 and the lower end of said cam lever is guided thereby. A 55 cam 120 is mounted upon said shaft in front of the cam lever 117 and has a cam groove 121 formed upon the rear surface thereof. A roller 122 is rotatably mounted upon the cam lever 117 and engages said groove. The 60 lower end of the cam lever is disposed between the bearing 119 of the shaft and the rear face of the cam 120 and is held against lateral movement thereby. The shaft 118 extends through the bearing 119 and a sleeve 65 123 is fixedly mounted thereon by means of

a tapered pin 123'. The front surface of the sleeve engages the rear surface of the bearing 119 whereby said shaft is held against forward longitudinal movement. A shaft 124 engages the rear end of the hole in the 70 sleeve 123 and is mounted therein for longitudinal sliding movement. A key 125 mounted on said shaft 124 and slidably engaging a longitudinal slot in the sleeve forms a driving connection between said 75 shaft and sleeve. The shaft 124 extends rearwardly and engages a bearing 126 in the bearing structure 60, and extends through the bearing 126 and has a gear 127 mounted thereon at the rear of the bearing 80 and meshing with the gear 61 hereinbefore described. The gear 127 engages the rear surface of the bearing 126 and a collar 128 is secured on the shaft in front of the bearing 126 and engages the front surface 85 thereof, and the shaft is held against lateral movement thereby. The gear 127 is the same size as the gear 44. By reason of the fact that the gears 44 and 127 are the same size and that the gears 46 and 61 are the 90 same size, the shaft 124 and the shaft 39 will rotate at the same speed.

95 A clutch collar 129 is slidably keyed upon the shaft 39. Said clutch collar has a projection 130 upon the side adjacent the gear 35 which is adapted to engage a projection 131 formed upon said gear 35 when the clutch collar is moved toward said gear 35. Thus, it will be noted, that a driving connection is established between the shaft 13 100 and the spools 108, and the cam lever 117 through the engagement of the clutch collar 129 with the projection 131 on the gear 35. The bellows 55 and 63 are also driven through the clutch collar 129 for purposes 105 hereinafter described.

110 A polish reservoir 132 is secured upon the partition 9 on either side of the shoe supports 5. Another polish reservoir 133 is mounted upon said partition 10 between the shoe supports. A pair of polish reservoirs 134 are mounted upon the movable frame 69 in front of the shoe supports 5. The polish reservoirs 132, 133 and 134 are adapted 115 to contain liquid polish and are disposed in the same horizontal plane and a number of pipes 135 inter-connect them so that the polish therein will distribute itself throughout all of the reservoirs and maintain an equal level of polish therein. The pipes 135 which connect the polish reservoirs 132 and 134 are flexible so that the frame 69 may be moved. A filler pipe 136 leads through the wall of the body from one of the reservoirs 132 for filling the polish reservoirs from the outside of the body. A number of vertical pipes 137 are disposed in the polish reservoirs and have their upper ends open and extending above the side walls of the reservoirs, see Fig. 12. Each pipe 137 has a nozzle 130

- zle of an air pipe 138 disposed adjacent the top opening thereof adapted to create a vacuum in the pipes 137 when air is forced out of the nozzles so that the polish is drawn up through the pipes 137 and sprayed upon shoes resting on said shoe supports. The air pipes 138 of the reservoirs 132 and 133 communicate with the outlet 68 of the bellows 63 through a branching pipe 139. The air pipes 138 of the reservoirs 134 communicate with the outlet 69 of the bellows 55 through a pipe 140. As will be noted in the drawings the sprayers of the reservoirs 132 and 133 are sufficient to spray polish upon the sides of shoes resting upon said shoe supports 5, and the sprayers of the reservoirs 134 are positioned to spray polish upon the front of shoes resting upon said shoe support.
- 20 Secured to the rear side of the partition 9 and disposed in the paths of the bristles 25 of the brush members 24 are a pair of agitating members 141. These members agitate the bristles 25 as the brushes are reciprocated and serve to clean the brushes. This agitation of the bristles creates more or less dust and an air circulating mechanism 142 is disposed above the brushes and has its intake 143 disposed adjacent the agitating members 141 so that the dust laden air passes into the air intake 143. The air circulating mechanism 142 is of usual construction and comprises a rotary fan 144 disposed within the casing 145 and driven by an electric motor 146. The casing 145 communicates with the intake 143 and has an outlet 147 which leads into a bag 148 of porous material. When the fan is rotated the air is taken into the intake and passes through the casing 145 and outlet 147 into the bag 148 and through the sides of the bag leaving all dust, held in suspension, within the bag.
- 25 Journaled in bearings 149, which are secured upon the sides of the body 1, is a controlling shaft 150. This shaft is driven from the shaft 30 of the motor 12 through a reducing gear train 151, whereby the controlling shaft makes one revolution for a complete operation of the machine. Mounted upon the shaft 150 is a cam 152 which has a relatively small raised portion 153 thereon. A bell crank lever 154 is pivoted upon a bracket 155 which is secured to the partition 11. A cam roller 156 is mounted upon one arm of the bell crank lever and engages the surface of a cam 152 mounted on said shaft 150. A connecting rod 157 is pivoted upon the other arm of the bell crank lever and extends downwardly therefrom through the partition 11. A spring 158 has its one end connected to the last mentioned arm of the bell crank lever and its other end secured to the partition 11 whereby the roller 156 is held in proper engagement with the cam 152. A second bell crank lever 159 is pivoted in a bearing 160 which is secured to the structure of one of the bearings 14. One arm of the bell crank lever 159 has a stud 159' thereon engageable with an annular groove 161 of the clutch collar 129. The other arm of said bell crank lever 159 is pivotally connected to the lower end of the connecting rod 157 and cam 152 controls the position of the clutch collar 129 thereby.
- 30 An arm 162 is mounted upon the shaft 150 and is adapted to contact a stationary segmental ring 163 which is secured to the body concentric with the shaft 150. The arm 162 is adapted to contact the segmental ring during a greater portion of the rotation of the shaft 150 and to be out of contact with said ring as it passes over the gap 164 therein. A contact lever 165 is pivoted upon the wall of the body adjacent said gap and is adapted to contact the arm 162 as it passes over said gap. A spring 166 serves to hold the contact lever 165 out of the path of the arm 162. A handle 166' is pivoted in said body and is connected to the contact lever 165 by means of an arm 166'', mounted on the hub of the handle 166', and a connecting rod 165' having its front end pivotally connected to said arm 166'' and having its rear end pivotally connected to an arm of the contact lever 165, so that a person sitting in the seat 3 may operate the contact lever to start the mechanism.
- 35 As is designated in Fig. 3, the contact lever 165 and the segmental ring 163 are in metallic contact with each other by means of a conductor 167. The conductor 167 is connected with a source of electric energy 168 by means of a conductor 169. A brush wheel 170 is formed on the hub of the arm 162. A brush 171 contacts said brush wheel and a conductor 172 leads therefrom to one terminal of the motor 12. The other terminal of the motor 12 is connected to the source of energy 168 by means of a conductor 173. A conductor 174 leads from the conductor 173 to one terminal of the motor 146. A conductor 175 leads from the other terminal of said motor 146 to a stationary contact 176 which is adapted to be engaged by a contact 177 mounted upon an extension of the bell crank lever 154. The contact 177 is in electrical communication with the brush wheel 170 by means of a conductor 177' for purposes hereinafter described. The contact portion of the arm 162 and the brush wheel 170 and the contact 177 are insulated from the controlling shaft 150 as designated.
- 40 The operation of the device is as follows: A person wishing his shoes polished sits in the seat 3 and places his shoes upon the shoe supports 5. He then operates the handle 166' to contact the lever 165 with the arm 130

162. Said arm 162 always comes to rest over the gap 164 of the segmental ring 163 to stop the mechanism by reason of the fact that current is cut off from the motor 12 when the arm 162 passes over the gap 164. The circuit is closed when the contact lever 165 contacts the arm 162 and the motor 12 is started. The shaft 150 driven by the motor rotates the arm 162 and said arm 10 soon passes beyond the gap 164 and engages the segmental ring 163 whereupon the handle 166 may be released to move the contact lever 165 to an inoperative position. The cam 152 is so positioned relative to the arm 15 162 and the gap 164 of the segmental ring 163 that the raised portion 153 of the cam engages the cam roller 156 as the arm 162 passes through the gap 164 so that upon the initial rotation of the motor 12 the 20 clutch collar 129 is positioned out of engagement with the projection 131 of the gear 35, and the shaft 33 remains stationary. While the bell crank lever 154 is in this position the motor 12 actuates only the brush members 25 24, and said brushes serve during this initial operation to brush the shoes and remove dust and dirt therefrom. While the bell crank lever 154 is in this position the contact 177 is in engagement with the contact 176 and a circuit is complete through the motor 146 whereby the air circulating means is actuated to gather dust removed from the brushes 24 and from the agitating members 141. As the motor 12 continues to 30 rotate the cam 152 moves so that the roller 156 engages the lower portion thereof, whereupon the clutch collar 129 is moved into engagement with the projection 131 of the gear 35, and the contact 177 moves out 35 of engagement with the contact 176 thereby stopping the air circulating mechanism 142. As the motor 12 continues to revolve the shafts 39 and 85 are rotated and their connected parts actuated. When the clutch 40 129 is in engagement with the projection 131 the bellows 55 and 63 are actuated to force air through their respective air pipes 138 to spray polish upon the shoes as hereinafter described. As above stated the bellows actuate 45 the sprayers of the reservoirs 132 and 133, which spray polish upon the sides of the shoes. The actuation of the bellows 63 is so timed that polish is sprayed upon the shoes when the brush members 24 are withdrawn 50 from engagement with the shoes. 55 At this stage of the operation, the mechanism mounted upon the removable frame 69 is also actuated. This mechanism serves to supplement the brush members 24 in polishing the front of the shoes. The operation of this supplemental polishing means is as follows. After each polishing operation, that is when the arm 162 passes over the gap 164 and the mechanism is stopped, the tilting 60 frame rests in its upper position so that the 65 shoes upon the shoe supports 5 may be withdrawn therefrom. A shield 178 extends over the spools 108 and 114 to protect the same and the belt element 111 as shoes are placed upon the shoe supports or withdrawn therefrom. Said cam 120 is so timed respecting the reciprocations of the brush members 24 that the tilting frame is lowered to engage the belt element 111 with the shoe as the brushes 24 are withdrawn from the shoe. As 70 before described the shaft 85 is driven alternately at opposite directions to unwind the polishing element 111 from one spool to the other and then to rewind it back. This movement of the polishing element 111 is 75 continuous during this stage of the operation of the mechanism and rubs the surface of the shoes as the cam 120 moves the tilting frame to its lower position. By reason of the fact that the spools 108 have a resilient 80 connection with their shafts 100 a greater or less portion of the polishing element may be unwound from the spools so that the cam 120 may move the tilting frame to its lower position. When the spools 108 and 114 are 85 positioned below the shoes the polishing element 111 is wrapped around the shoes, thus contacting practically the entire surface of the front of the shoes. See Fig. 4. 90 When this supplemental polishing element 95 is actuated the bellows 55 is also operated to spray polish from the reservoirs 134 upon the front ends of the shoes, and the cam groove 48 is so timed relative to the movements of the tilting frame that polish is 100 sprayed from the reservoir 134 when the tilting element 111 is out of contact with the surface of the shoes. 105 The mechanism continues to be driven by the motor 12 until the arm 162 passes over the gap 164 of the supplemental ring and opens the circuit to the motor 12. The motor then comes to a stop and the machine is set for another polishing operation. 110 The supplemental polishing mechanism, as 110 above described, is mounted upon the movable frame 69. A pair of studs 178 are secured to the front wall of the body and extend longitudinally of the path of the movable frame. The rear ends of the studs 178 115 engage apertures of brackets 178' of the base 70 of the movable frame. Coil springs 180 encircle the studs 178 and abut the face of the brackets 178' and the adjacent front wall of the body with their respective ends, 120 whereby the movable frame tends to move to the rear extremity of its path of movement. An extension arm 181 mounted on the movable frame 69 is provided for each shoe support and a rearwardly extending 125 slide stud 182 is formed on each extension and engages a respective slide 183 formed on each shoe support 5. Each extension arm 181 has an upwardly extending projection 184 disposed in front of the respective shoe 130

support, which is adapted to be engaged by the front of the sole of a shoe on said shoe supports. By the above described mechanism it will be seen that the movable frame 5 69 may be positioned by the engagement of shoes on said shoe supports with the projections 184. This mechanism allows the movable frame to accommodate itself to any size of shoe so that the supplemental polishing mechanism will properly engage the 10 shoes.

Having thus fully described my invention, I claim:—

1. In a shoe polishing machine, the combination with a shoe support, of a movable frame, polishing means mounted on said movable frame, an extension arm on said movable frame adapted to be engaged by the front of a shoe on said support, a spring 15 means adapted to position said movable frame with said extension arm in engagement with the front of a shoe.

2. In a shoe polishing machine, the combination with a shoe support, of a movable frame, polishing means mounted on said frame, means for intermittently engaging said polishing means with a shoe on said support, and means engageable with the shoe on said support for positioning said frame 25 for proper engagement of the polishing means with the shoe.

3. In a shoe polishing machine, the combination with a shoe support, of a movable frame, a tilting frame mounted on said movable frame, polishing means mounted on said tilting frame, means for moving said tilting frame for intermittently engaging said polishing means with a shoe on said support, and means engageable with the shoe 35 40 on said shoe support for positioning said movable frame for proper engagement of the polishing means with a shoe.

4. In a shoe polishing machine, the combination with a shoe support, of a movable brush element adapted to intermittently engage the surface of a shoe on said support, driving means therefor, a movable frame, a supplemental polishing means movably mounted on said frame, means having operable connection with said driving means for intermittently engaging said supplemental polishing means with a shoe when said brush element is out of engagement with the shoe, and means engageable with the shoe for 45 55 positioning said movable frame for proper engagement of the supplemental polishing means with the shoe.

5. In a shoe polishing machine, the combination with a motor, of a movable brush element, a driving connection between said motor and said brush element, a controlling shaft, a driving connection between said motor and said controlling shaft including a reducing gear train, means for applying 60 65 polish, a driving connection between said

polish applying means and said first mentioned driving connection including a clutch element, a cam on said controlling shaft, and a lever actuated by said cam and having an operable connection with said clutch element 70 whereby said polish applying means is rendered inactive for a predetermined period.

6. In a shoe polishing machine, the combination with a motor, of a movable brush element, a driving connection between said motor and said brush element, a controlling shaft, a driving connection between said motor and said controlling shaft including a reducing gear train, means for applying polish, a supplemental polishing means in 80 driving relation with said means for applying polish, a driving connection between said movable brush element and said polish applying means including a clutch element, a cam on said controlling shaft, a lever 85 actuated by said cam and having an operable connection with said clutch element whereby said polish applying means and said supplemental polishing means are rendered inactive for a predetermined period. 90

7. In a shoe polishing machine, the combination with a motor, of a movable brush element adapted to intermittently engage a shoe, a driving connection between said motor and said movable brush element, a controlling shaft, a driving connection between said motor and said controlling shaft including a reducing gear train, a supplemental polishing element, means for intermittently engaging said supplemental polishing element 95 100 with the shoe when said brush element is out of engagement therewith, means for applying polish on the shoe, a driving means for said supplemental polishing element and said polishing applying means, a driving connection between said first mentioned driving connection and said driving means, a driving connection between said first mentioned driving connection and said driving means including a clutch element, a cam mounted 105 on said controlling shaft, a lever actuated by said cam and having an operable connection with said clutch element, a stationary segmental ring disposed in axial alignment with said controlling shaft, an arm mounted 110 on said controlling shaft and adapted to contact said arm to complete an electrical circuit through said motor, and means for completing the circuit through said motor when said arm is passing over the gap in said segmental ring, said arm being in timed relation with said cam whereby said supplemental polishing applying means are rendered inactive during the initial movements of 115 120 125 said brush element.

8. In a shoe polishing machine, the combination with a motor, of a movable brush element adapted to intermittently engage a shoe, a driving connection between said motor and said movable brush element, 130

- means for cleaning said brush element, a motor for actuating said cleaning means, a controlling shaft, a driving connection between said motor and said controlling shaft 5 including a reducing gear train, a supplemental polishing element engageable with the shoe when said movable brush element is out of engagement therewith, means for applying polish on the shoe, a driving means 10 for said supplemental polishing element and said polish applying means, a driving connection between said first mentioned driving connection and said driving means including a clutch element, a cam mounted on said controlling shaft, a lever actuated by said cam and having an operable connection with said clutch element, a stationary segmental ring disposed in axial alinement with said controlling shaft, an arm mounted on said 15 controlling shaft, a switch in operable relation with said lever, a circuit including said first mentioned motor said arm and said segmental ring, a second circuit including said second mentioned motor said switch, said arm and said segmental ring, and means 20 for completing the circuit through said first mentioned motor when said arm is passing over the gap in said segmental ring, said arm being in timed relation with said cam whereby said supplemental polishing ele- 25 30 35 ment and said polish applying means are rendered inactive during the initial movement of said movable brush element, said switch being adapted to be closed when said lever is positioned by said cam to render said polish applying means and said supplemental polishing element inactive.

In testimony whereof I affix my signature.

JOHN H. BECK.
